(57) **CLAIM**

The ornamental design for a body fat analyzer with scale, as shown and described.

DESCRIPTION

FIG. 1 is a perspective view of the first embodiment of a body fat analyzer with scale showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a perspective view showing a condition in which the handle is removed thereof;

FIG. 9 is a front elevational view showing a condition in which the handle is removed thereof;

FIG. 10 is a rear elevational view showing a condition in which the handle is removed thereof;

FIG. 11 is a top plan view showing a condition in which the handle is removed thereof;

FIG. 12 is a bottom plan view showing a condition in which the handle is removed thereof;

FIG. 13 is a right side elevational view showing a condition in which the handle is removed thereof;

FIG. 14 is a left side elevational view showing a condition in which the handle is removed thereof;

FIG. 15 is a perspective view of the second embodiment of a body fat analyzer with scale showing our new design;

FIG. 16 is a front elevational view thereof;

FIG. 17 is a rear elevational view thereof;

FIG. 18 is a top plan view thereof;

FIG. 19 is a bottom plan view thereof;

FIG. 20 is a right side elevational view thereof;

FIG. 21 is a left side elevational view thereof;

FIG. 22 is a perspective view showing a condition in which the handle is removed thereof;

FIG. 23 is a front elevational view showing a condition in which the handle is removed thereof;

FIG. 24 is a rear elevational view showing a condition in which the handle is removed thereof;

FIG. 25 is a top plan view showing a condition in which the handle is removed thereof;

FIG. 26 is a bottom plan view showing a condition in which the handle is removed thereof;

FIG. 27 is a right side elevational view showing a condition in which the handle is removed thereof; and,

FIG. 28 is a left side elevational view showing a condition in which the handle is removed thereof.
